UNITED STATES PATENT OFFICE.

GEORG MERLING, OTTO CHRZESCIUSKI, AND OTTO PFEFFER, OF ELBERFELD, GERMANY,
ASSIGNORS TO SYNTHETIC PATENTS CO. INC., OF NEW YORK, N. Y., A CORPORATION
OF NEW YORK.

ALKALI-METAL ACETONES.

1,169,341.

Specification of Letters Patent.

Patented Jan. 25, 1916.

No Drawing.

Application filed July 7, 1914. Serial No. 849,608.

To all whom it may concern:

Be it known that we, GEORG MERLING, professor of chemistry, doctor of philosophy, and OTTO CHRZESCIUSKI and OTTO PFEFFER, doctors of philosophy, chemists, citizens of the German Empire, residing at Elberfeld, Germany, have invented new and useful Improvements in Alkali-Metal Acetones, of which the following is a specifica- 10

We have found that the hitherto unknown technically very valuable alkali metal ketones, such as sodium acetone having most probably the following formula:

can be obtained by treating ketones such as acetone, methylethylketone, diethylketone, methylpropylketone, cyclohexanone, cyclopentanone, at a temperature below zero with alkali amid or an alkali metal (Na, K).

The new compounds are crystalline products. The lower members of the series, such as sodium acetone, are readily soluble in ether as the member of carbons increases they become less soluble in ether. They are distinguished by being exceptionally chemically active and are only stable at a low temperature.

In order to illustrate the new process more fully the following example is given, the parts being by weight: 600 parts of absolute ether are thrown over 40 parts of pulverized sodium amid and the mixture is cooled down to -20° C. When this temperature is reached 58 parts of dry acetone are slowly added to the reaction mass, which has to be stirred, care being taken that the temperature does not rise above -15° C. The sodium amid dissolves. After the whole acetone has been added the mixture is still further stirred during one hour and then the ether is distilled off *in vacuo*. The sodium acetone remains in the freezing mixture as a colorless crystalline product which is stable only below 0° C., and which decomposes at ordinary room temperatures. With acetylene it forms the hitherto unknown 3-methylbutinol having most probably the formula:

In order to produce this product in the

suspension of sodium acetone in ether a current of acetylene is conducted. The brownish solution is poured into well cooled dilute acetic acid which has to be stirred. The etheral layer contains the 3-methylbutinol. It is an almost colorless oil boiling at 105-106° C. In a similar manner other groups, homologous or analogous to the oxyisopropyl group, such as:

can be introduced into hydrocarbons *e. g.* acetylene. In this manner *e. g.* from ethylmethylketone-sodium and acetylene the 3-methylpentinol:

which is an oil boiling at from 120-121° C.; from diethylketone-sodium and acetylene the 3-ethylpentinol:

which is an oil boiling at from 135-137° C.; from methylpropylketone-sodium and acetylene the 3-propylbutinol:

which is an oil boiling at from 137-138° C.; from cyclopanone-sodium and acetylene the acetylene-carbinol:

can be obtained.

Instead of acetylene other hydrocarbons can be used, and instead of acetone other carbonyl-containing bodies *e. g.* acetic ester, methylethylketone, acetic aldehyde, etc.

We claim:

1. The new alkali metal ketones being colorless crystalline products more or less soluble in ether and being very chemically active substances by means of which the oxyisopropyl or similar groups can be introduced into hydrocarbons, substantially as described.

2. The new sodium acetone having most probably the formula:

5

being a colorless crystalline compound, stable only below 0° C., soluble in ether and being a chemically very active substance; forming 3-methylbutinol with acetylene, 10 substantially as described.

In testimony whereof we have hereunto set our hands in the presence of two subscribing witnesses.

GEORG MERLING.

FRANCES NUFER.

Corrections in Letters Patent No. 1,169,341.

It is hereby certified that in Letters Patent No. 1,169,341, granted January 25, 1916, upon the application of Georg Merling, Otto Chrzesciuski, and Otto Pfeffer, of Elberfeld, Germany, for an improvement in "Alkali-Metal Acetones," errors appear in the printed specification requiring correction as follows: In the grant and in the printed specification, the name of the second-mentioned patentee, for "Otto Chrzesciuski" read *Otto Chrzescinski*; page 1, line 92, for the word "cycloopenanone" read *cyclopentanone*; page 2, line 9, claim 2, for "3-mythylbutinol" read *3-methylbutinol*; and that the said Letters Patent should be read with these corrections therein that the same may conform to the record of the case in the Patent Office.

Signed and sealed this 18th day of April, A. D., 1916.

[SEAL.]

R. F. WHITEHEAD,

Acting Commissioner of Patents.

Cl. 23—24.
